UNITED STATES PATENT OFFICE.

STURGES WHITLOCK, OF SHELTON, CONNECTICUT, ASSIGNOR TO THE WHITLOCK MACHINE COMPANY, OF DERBY, CONNECTICUT.

FORM-SUPPORTING BED FOR PRINTING-PRESSES.

SPECIFICATION forming part of Letters Patent No. 637,055, dated November 14, 1899.

Application filed May 23, 1899. Serial No. 717,945. (No model.)

To all whom it may concern:

Be it known that I, STURGES WHITLOCK, of Shelton, in the county of Fairfield and State of Connecticut, have invented a new Improvement 5 in Form-Supporting Beds for Printing-PresSES; and I do hereby declare the following, when taken in connection with the accompanying drawings and the letters of reference marked thereon, to be a full, clear, 10 and exact description of the same, and which said drawings constitute part of this specification, and represent, in—

Figure 1, a reverse plan view of one form which my improved bed may assume; Fig. 2, 15 a view thereof in front elevation; Fig. 3, a broken sectional view thereof; Fig. 4, a broken plan view of one of the modified forms which the bed may assume; Fig. 5, a broken sectional view thereof.

20 My invention relates to an improvement in form-supporting beds for flat-bed printing-machines, the object being to produce a light and compact bed constructed with particular reference to rigidity and to convenience in 25 securing parts to it.

With these ends in view my invention consists in a form-supporting bed having certain details of construction and combinations of parts, as will be hereinafter described, and 30 pointed out in the claims.

For the illustration of my invention I have chosen to show and describe a form-supporting bed adapted for use in connection with a flat-bed printing-press in which the bed and 35 the form supported by it are moved back and forth beneath a rotating cylinder; but my improved bed is equally applicable for use in that class of presses in which the bed and form are fixed and in which the cylinder 40 moves back and forth over them.

Before proceeding to the description of my improvement it may be well for me to state that heretofore form-supporting beds for presses of the kinds described have generally 45 comprised a top plate reinforced by ribs formed upon its lower surface. Ribbed beds of the type described are objectionable because they lack rigidity and yield under the pressure of printing, necessarily to the detriment 50 of the operation of the machine and its product. Obviously a printing-press requires

that its bed shall be as nearly rigid as it is possible to make it for the unyielding support of the form printed from. In the use of ribbed beds such as described the extension 55 strains fall upon the ribs which are beneath, while the compression strains fall in the plate which is on top. In order that the ribs shall be heavy enough to resist the said extension strains, it is necessary to employ so many and 60 to make them so deep in their downward extension that the beds become objectionable not only in size, but also in weight. Furthermore, ribbed beds are always objectionable on account of the difficulty of securing to them 65 the necessary parts—such, for instance, as the shoes, the rack, and the lugs for the air-spring plungers.

In carrying out my invention, as shown in Figs. 1, 2, and 3 of the drawings, I form the 70 box-like bed with a top plate A and a bottom plate B, which, although corresponding in general form to and coextensive with the top plate, is by preference made thicker than the same to enable it to perfectly resist the heavier 75 strain imposed upon it owing to the fact that on account of its position it becomes the extension-plate, as distinguished from the top plate, which is the compression-plate. These two plates are connected together by integral 80 ties located within the space separating the two plates and consisting, as shown, of ribs C and vertical posts D. The said ribs are arranged parallel with the lines on which the shoes E and rack F are attached, the shoes 85 being secured in place by screws c and the rack by bolts and nuts d. The bottom plate is also furnished with depending lugs G G for the attachment of the air-spring plungers commonly used with the beds of such presses. 90 The vertical posts D are distributed between the ribs C and will of course be employed in such numbers and such arrangement as found desirable. The edges of the bed are formed by side walls H, which unite the edges of the 95 two plates. The completed bed, in fact, resembles a very shallow box filled to a greater or less extent with braces formed integral with its top and bottom. The holes I in the side walls H of the bed and the holes J in the bottom plate B thereof are incidents in their formation to the process of coring the bed in cast- 100

ing it. They do not, however, sensibly affect the rigidity of the finished bed.

I have shown the lugs for the air-spring plungers as cast integral with the bottom of the plate; but it is obvious that they may be made independently of and bolted thereto, if preferred.

In the construction shown by Figs. 4 and 5 of the drawings the upper plate K and the lower plate L are united by means of transversely-arranged ribs M, which take the place of combined ribs and posts in the construction first described. Instead of using ribs and posts combined or ribs alone I might use posts alone or some other form of integral ties for uniting the upper and lower plates.

I would therefore have it understood that I do not limit myself to the exact construction herein shown and described, but hold myself at liberty to make such changes as fairly fall within the spirit and scope of my invention. I am aware, however, that skeleton beds, broadly speaking, are old, and also that a prior patent shows a skeleton form-supporting bed for a flat-bed and cylinder printing-press. I do not, therefore, claim such a construction broadly.

Having fully described my invention, what I claim as new, and desire to secure by Letters Patent, is—

1. A box-like form-supporting bed for flat-bed printing-presses, comprising an imperforate top plate, a coextensive bottom plate, integral walls uniting the edges of the two plates, integral ties located in the hollow space between the two plates for uniting the same, and including posts and longitudinal and transverse ribs, fastening devices depending from the lower face of the lower

plate, and shoes located upon the lower face 40 of the lower plate, parallel with the said longitudinal ribs.

2. A box-like form-supporting bed for flat-bed printing-presses, comprising an imperforate top plate, a coextensive bottom plate 45 thicker than the top plate, and integral ties located in the hollow space between the two plates, and uniting the same.

3. A box-like form-supporting bed for flat-bed printing-presses, comprising an imperforate top plate upon which the form is placed, a bottom plate coextensive with the top plate, and integral post-like ties located in the hollow space between the two plates and uniting the same. 50

4. A box-like form-supporting bed for flat-bed printing-presses, comprising an imperforate top plate, a bottom plate coextensive therewith, and integral ties located in the hollow space between the two plates for uniting 60 the same, and including posts and ribs.

5. A box-like form-supporting bed for flat-bed printing-presses, comprising an imperforate top plate, a coextensive bottom plate, integral walls uniting the extreme edges of the 65 two plates, integral ties located in the hollow space between the two plates for uniting the same, fastening devices depending from the lower face of the lower plate, and shoes located upon the lower face of the lower plate 70 parallel with the length thereof.

In testimony whereof I have signed this specification in the presence of two subscribing witnesses.

STURGES WHITLOCK.
